APPARATUS FOR SPRAYING METALS

Harold R. Forton, Detroit, Mich.

Application December 19, 1935, Serial No. 55,173

6 Claims. (Cl. 83—91)

This invention relates to apparatus for atomizing and spraying molten metal, and aims to provide in very compact and readily portable hand or "gun" form, metal spraying equipment of especially convenient and reliable character.

An aim of particular importance in developing the present invention has been the provision, in a device of the character indicated, of electrical heating means, means for automatically feeding the metal in wire or strip form, and automatically operable controlling means for the heating element enabling holding constant temperature in the crucible regardless of whether the machine is idle or in use, and by means of which the device may be kept in instantaneously operable condition at all times.

Another important object of the invention is the provision of such a device which may be easily and quickly cleaned, in which the metal is delivered, melted and discharged continuously at the same rate, and projected practically immediately upon melting rather than stored in the instrument, as a result of which oxidation, and the clogging at the nozzle which it causes in many types of metal spraying equipment, are prevented.

Another object is a device of the sort indicated in which the nozzle may be cleaned quickly and easily, without removing it from the apparatus, and in which the conveying tube for the metal, together with the nozzle, may at any time and whether hot or cold be instantly removed and replaced.

Another object comprises the provision of such a spraying device incorporating air blast means for discharging molten metal, together with electric metal heating means, and provided with automatic switching means responsive to the turning on and off the air blast for reducing the wattage when the air is turned on, in a fashion which automatically maintains the metal-melting portions at uniform temperatures regardless of the presence or absence of the air blast and its cooling effect, the arrangement being such that the air blast when operating prevents the heating element from burning out although the element is operated above the capacity at which it could be rated to operate without artificial cooling. A related object is the provision in conjunction with the means last mentioned of automatic operating means for starting and stopping the metal feeding apparatus when the air blast is turned on and off.

Other objects and advantages will be apparent from the following description, wherein refer-

ence is made to the accompanying drawing illustrating a preferred embodiment of my invention, and wherein similar reference numerals designate similar parts throughout the several views.

In the drawing:

The single figure is a partly diagrammatic view showing in longitudinal section the spraying device and the control box containing the automatic regulating apparatus, showing schematically the connections between these elements and the operating motor for the metal feed.

Referring now to the drawing, reference character 10 represents a casing, the front or bottom face of which is substantially but not entirely closed, and centrally apertured as at 14 to provide an air jet opening which is also partly defined by the spacedly interfitting nozzle 15 through which the metal is discharged, the metal being drawn therethrough and aspirated by the air blast. An air delivery chamber 18 surrounding the nozzle and jet opening is formed in the front wall portion 20 by which plate 12 is carried, such plate closing the front of the chamber. The air may be conducted to the chamber for discharge through the air jet opening by an air tube 22, which may pass through the hollow handle 25.

The wall 20 is secured to the casing by screws 26 but spaced therefrom to provide a passage 27 through which air may enter the casing from beneath. A vent 28 is also preferably provided in the back wall of the casing, the vent being shown guarded by a hat 29 pivoted to the back wall in such fashion that it may be swung free of the vent.

The metal to be melted, designated 30, may also be fed through the hollow handle, in wire form, a conveyor tube as 32 being provided therefor arranged to discharge it directly into the open upper end of the crucible 33. The metal is advanced by friction feeding rolls as 35, driven by worm or other suitable gearing 37 turned by a flexible shaft 38, which may also extend from the end of the hollow handle to a driving motor 40, which may be carried upon a work bench (not shown) or other suitable fixed support.

The crucible is not intended at any time to hold a reserve supply of metal, the parts being so proportioned that the metal merely passes therethrough, being melted and discharged as rapidly as delivered. The discharge nozzle 15, formed integrally with the crucible, communicates directly with the interior thereof, a frusto-conical or equivalently shaped bottom being pro-

vided in the crucible so that a cleaning wire may be passed through the nozzle from above, by merely swinging the hat 29 out of the way and pushing the wire through the crucible from the upper end, the shape of the bottom of the crucible guiding the wire into the nozzle. The outside of the nozzle is smaller than either the air jet opening 14 or the opening in wall 20, and the passage from the interior of the casing to the air jet communicates with an annular opening 35 formed in the bottom of the crucible and partly overlying the wall 20. The crucible rests loosely in place, as does also the electrical heating unit assembly surrounding the same and generally designated 40. A small quantity of heated air may accordingly leak beneath the crucible and heating element and into the chamber 35, whence it may pass out through the air blast nozzle, traveling in direct contact with the metal discharge nozzle 15 and forming thereabout a skin or thin layer of highly heated air which prevents undue cooling of the metal in the nozzle by the air blast.

The conveyor tube 32, although shown as blocking removal of the crucible from the rear when in operative position, is preferably so held in place that it may be slid back into the handle and out of the way, being releasably supported in a bracket 41 and held by a set screw 42. When the tube is slid back the crucible may be quickly removed and replaced. The heating element is shown as a tapped coiled resistance wire 45 held between refractory sleeves 48-49, although it might of course be wound and supported in any other suitable fashion. The crucible fits slidably within the inner coil form.

By reason of the intermediate tap (connected to wire 72b) the heating element is divided into upper and lower sections, designated 45a and 45b. These are so proportioned that when operated in series they are capable of holding the crucible at the proper temperature for melting the metal when the air blast is not in operation, while when only the section 45b is in operation, and the entire current is passed therethrough, the wattage being of course greatly increased, the greater rate of heat delivery is such that the desired temperature of the crucible may be maintained with the air blast in operation.

A main valve 50 is provided in the air line, and the current supply for the motor and heating element is indicated as controlled by a hand switch 51.

Automatic switching means is also provided for so controlling the heating element operation as to increase its wattage when the air blast is turned on, by shorting out the upper section 45a, and decrease the wattage by opening the short-circuit to place both sections (45a-45b) in series when the air blast is shut off. Such switching means includes a pressure cylinder 55, connected to the air supply line between the main valve 50 and the nozzle, as by means of air hose 56, a piston 57 reciprocable in the cylinder and operable by the back pressure from the air nozzle to throw switch blades 60-61 into shunting relation with respect to contacts 62-63 and 64-65. The switch blades are carried by an insulating disc 68 mounted upon the end of piston rod 69 which extends from cylinder 55. The air cylinder and switching means are shown mounted in a single casing 70 which is intended to be carried upon the bench or wall in fixed position and connected to the spray gun by flexible conduits 56, 72, the latter carrying the wires, designated 72a-72b

and 72c, for the heating element. When the air pressure is shut off the piston is returned and the shunt circuits opened by a spring 74 trapped and acting upon the piston rod. Power leads 75-76, connected to contacts 65-62, respectively are also directly connected to the ends of heating coil 45, so that when the shunt switches are open and the current on, the entire coil is energized. One terminal of the motor 40 is connected to contact 63, the motor being thus energized only when contacts 62-63 are bridged by switch blade 60. Contact 64 is connected to wire 72b which runs to the center tap of the heating element.

It will be seen that when switch blade 61 connects contacts 64-65, wires 72b-72c are bridged and the upper section 45a of the heating element short-circuited, the motor 40 being simultaneously energized, since the switches 60-61 operate together.

Although the operation will doubtless be clear from the foregoing, it may be briefly summarized as follows: If desired, switch 51 may remain closed and the current be supplied continuously, in which event the crucible remains hot and ready for instant operation, even though valve 50 be closed. Under such conditions switch blades 60-61 occupy the positions in which they are shown in the drawing, the shunt circuits between contacts 62-63 and 64-65 remaining open, the motor deenergized and current flowing through the entire heating coil. When it is desired to operate the gun, the valve 50 is opened, which immediately applies pressure to the piston, closing switches 60-61 shorting out heating coil section 45a and imposing the entire current upon section 45b, the temperature and heat delivery of which is immediately greatly raised. The motor 40 being simultaneously started, metal is immediately delivered to the crucible, whence it is forced through the nozzle by atmospheric pressure, due to the reduction of pressure created at the mouth of the nozzle by the air blast, which also aspirates and projects the molten discharge. Heating coil section 45b is so proportioned that it would burn out but for the cooling influence of the air blast. For this reason it has the property of lagging but a very short time in reaching the increased temperature when section 45a is shorted out, and as quickly drops to the lower temperature when section 45a is again placed in circuit.

What I claim is:

1. In a device of the character described, in combination with means for supplying air under pressure and a source of electric current, a casing having an air jet opening therein, metal conveying and heating means within the casing including an electrical heating element surrounding a portion of the conveying means, and a nozzle portion for molten metal connected to the conveying means and having a discharge opening adjacent the air jet opening, means including an electric switch for changing the effective heat delivery of the heating element, and means responsive to a change of pressure in the air supply means for operating said switch.

2. In a device as set forth in claim 1, electrically operable means for feeding metal to the conveying means, switching means for controlling the operation of said electrically operable feeding means, and means for operating said last mentioned switching means also in response to change of pressure in the air supply means.

3. In combination with means for supplying

air under pressure, and a source of electric current, metal spraying means including a casing having an air jet opening therein connected to the air supply, a metal melting receptacle within 5 the casing, said casing also having a nozzle portion adjacent the air jet opening and connected to the metal melting receptacle for discharging molten metal, an electric heating element arranged to act upon said receptacle, means for 10 changing the effective heat output of said heating element including an electric switch, valve means for starting and stopping the air supply, and means responsive to starting and stopping of the air supply for operating said switch to increase 15 the heat output when the air supply is turned on, and to decrease the heat output when the air supply is turned off, the means for changing the heat output and the heating element being so proportioned to the air supply as to maintain 20 the temperature of the metal melting receptacle substantially constant by virtue of such

changes of heat output of the heating element.

4. Apparatus as set forth in claim 3 including electrically operable metal feeding means for supplying metal to said receptacle, and means for starting the metal feeding means when the air supply is turned on, and for stopping said feeding means when the air supply is turned off. 5

5. Apparatus as set forth in claim 3 including pressure-responsive means for throwing said switch connected to the air supply means between the valve and the air jet. 10

6. Apparatus as set forth in claim 3 including electrically operable metal feeding means for supplying metal to said receptacle, and means including a second switch for starting the metal feeding means when the air supply is turned on, and for stopping said feeding means when the air supply is turned off, and common pressure-responsive operating means for both of said switches connected to said air supply means. 15 20
